ABSTRACT: A self-anchoring hair curler comprising a unitary body having a center portion, and end portions having engaging areas of greater diameter than the center portion, protuberances extending from the center portion and engaging elements upstanding from the end portions, the elements having catching extremities, the elements intermeshing with taut hair roots and self-anchoring the curler adjacent the scalp.

A SELF ANCHORING HAIR CURLER

BACKGROUND OF THE INVENTION

1. Field of the Invention

This invention relates to the hair curlers and, more particularly, to hair curlers of the self-engaging type.

2. Description of the Prior Art

Self-engaging curlers have had a certain success because they are able to maintain hair rolled thereon in a tightly fixed roll without need for pins, clips or elastics. But curlers of this type have the disadvantage that the number of gripping elements required for effective self-engagement also have the cumulative effect of holding the hair too tightly so that removal of the curler is often difficult and accompanied by painful tearing of the hair. One suggested solution was to reduce the average density of the gripping elements on the center portion of the curler in relation to the density of such elements at the ends. This invention seeks to further improve this type of curler.

SUMMARY OF THE INVENTION

This invention provides a curler body having an area for rolling the hair distinct from the area of self-engagement. Thus, the hair curler of the invention comprises an elongated body portion having a center portion on which hair can be rolled and end portions joined to the center portion at its extremities. Both end portions extend longitudinally and have an exterior surface which is removed from the longitudinal axis of the curler beyond the exterior surface of the center portion. Engaging means disposed on those end portion exterior surfaces anchor the curler adjacent the scalp. In another form of the invention, outwardly extending protuberances are disposed adjacent the exterior surface of the center portion. These protuberances intermesh with the hair to aid in rolling the hair about the center portion and also tend to maintain the hair in a tight roll after the curler is fixed near the scalp by the engaging means on the end portions.

A further understanding of the invention is had from the several embodiments described below with reference to the drawings.

BRIEF DESCRIPTION OF THE DRAWINGS

FIG. 1 is an axial cross section of one form of the curler.

FIG. 2 is a view of this same curler in the position in which it is to be used.

FIGS. 3 to 6 show, in elevation, various forms for the protuberances on the center portion of the curler.

FIGS. 7 to 11 show, in elevation, various forms for the engaging elements on the end portions of the curler.

DESCRIPTION OF THE PREFERRED EMBODIMENTS

Referring to the FIG. 1, a hair curler comprises an elongated tubular body 10, which is formed of plastic or other suitable material. The curler includes a center portion 11 of smaller maximum outside diameter than the minimum outside diameter of adjacent cylindrical end portions 12 to define a circumferential recess between the end portions 12. The center portion 11 has an exterior surface 13 which is concave in longitudinal cross section. The center portion 11 is disposed between outwardly flared flange portions 14 at its lateral extremities, which integrally join the center portion 11 to the respective cylindrical end portions 12.

The center portion 11 may be provided with outwardly extending protuberances 15 which preferably extend radially outwardly from the curler body 10 are of the same material as the curler body 10 and are formed integrally therewith. These protuberances 15 intermesh with hair 16 rolled on the center portion 11 and aid in rolling the hair 16 and maintaining it in place in a tight roll when the curler is anchored near the scalp (see FIG. 2). These protuberances 15 can take one or more of the shapes shown in FIGS. 3 to 6; that is to say, in FIG. 3 conical and pointed 15, FIG. 4 conical with a swelling 17 at the tip,

FIG. 5 a semicircular strip 18, FIG. 6 a rectangular strip 19. The plane of the strips 18 and 19 are perpendicular to the axis of the curler.

The circumferential surfaces of the ends 12 of the body 10 are provided with engaging elements 20 designed to permit the anchoring of the curler near the scalp 21 by the gripping of the engaging elements 20 in the roots 22 of the hair 16, as shown in FIG. 2. Preferably, the engaging elements 20 are made of upstanding flexible filaments 23 of synthetic material whose ends are shaped like hooks 24. Such hooks 24 can be obtained by weaving a material of the pierced-looped type and then by cutting the loops laterally on one side, as shown in FIG. 8. It is also possible to make two lateral cuts, instead of just one, so as to eliminate a certain length of the filament of each loop, as shown in FIG. 9. The hooks 24 can also be obtained by forming a series of flexible filaments 23 of synthetic and preferably thermoplastic material in an "s" shape and by embedding one end 25 of the filament 23 in a base of plastic material 26. Such hooks 24 formed of flexible filaments 23 according to the FIGS. 8 to 10 are thus held by a woven base 27 or by a base formed of a sheet of plastic material 26. Such a base 26 or 27 is then cut into strips of appropriate width to form an engaging tape having the flexible elements 23 extending outward from one surface thereof. Thus one end of the filament 23 is secured in said tape and the other end is in the form of the engaging elements 20. The tape is secured to the circumferential exterior surface 28 of the respective end portions 12 as shown in the FIG. 1 by glue, solder or sewing, as desired.

The engaging elements 20 of FIG. 7 are hooks 29 having stems 30 integrally formed with the end portions 12 of the curler body 10. The stems 30 preferably extend out radially from the exterior surface 28 of the end portions 12 and their tips are readily formed, preferably by exposure to the thermal source, into the form of a hook 29 or a mushroom shape 31 of FIG. 11.

As seen in FIG. 2, since the diameters of the circumferential exterior surfaces 28 of the curler end portions 12 are greater than the maximum diameter of the concave exterior surface 13 of the center portion 11, hair 16 will be rolled only on the center portion 11. In addition, this construction permits a complete lock of hair to be rolled with substantially all of its bulk within the circumferential recess defined between the two end portions 12. Thus, when hair 16 is rolled tightly about the curler center portion 11, the engaging means 20 on the end portion exterior surface 28 can become engaged in the hair roots 22 to anchor the curler near the scalp 21. When removal is desired, a slight pull on the curler is sufficient to disengage the engaging means 20 from the hair roots 22. The hair 16 can then be unrolled without difficulty because it is not held in any other way.

Even if protuberances 15 are provided on central exterior surface 13 of the curler center portion 11, unrolling is still accomplished without difficulty since the protuberances 15 do not actually hold the hair 16. Rather, the protuberances 15 intermesh with the hair 16 to aid in rolling and maintaining a tight roll.

The curler described above can have small holes in the center portion 11 and flange portions 14. Such holes facilitate the drying of the hair by allowing the passage of air through the walls of those portions.

Numerous variations of this curler could be imagined. Thus, the flange portions 14 could be circular, joining the cylindrical end portions 12 to the center portion 11 which would be further elongated and which could also be absolutely cylindrical.

Another variation would be to form the curler body 10 of a more rigid type of the base 26 or 27. In this case, the protuberances 15 would be formed by straight-lined filaments 32 or 23 without the engaging elements 20; these being kept only around the end portions 12. It is also possible to cover the center portion 11 of the standard curler with the base 26 or 27 having only straight-lined filaments 32 or 23 without the engaging elements 20.

I claim:

1. A hair curler comprising an elongated tubular body of one-piece construction, the body including a center portion and end portions, the center portion having a maximum outside diameter substantially less than the minimum outside diameter of the end portions and defining a circumferential recess between the end portions; and hair engaging means provided only on the circumferential surface of each end portion and extending radially outwardly therefrom to anchor the curler adjacent the scalp after hair has been rolled about only the center portion of the curler, the entire bulk of the rolled hair being confined within the circumferential recess and being maintained out of contact with the hair engaging means.

2. A hair curler according to claim 1 wherein the hair engaging means comprise a plurality of upstanding hooking elements of flexible, resilient material.

3. A hair curler according to claim 2 wherein the hooking elements comprise filaments having bulbous tips.

4. A hair curler according to claim 1 wherein the hair engaging means are provided on a flexible tape, the tape being 20

secured to the circumferential surface of each end portion.

5. A hair curler according to claim 1 wherein the exterior surface of the center portion of the curler body is concave in longitudinal cross section.

6. A hair curler according to claim 1 further including a plurality of outwardly extending protuberances disposed about the exterior surface of the center portion, the protuberances aiding in maintaining the rolled hair in place about the exterior surface of the center portion.

7. A hair curler according to claim 6 wherein the protuberances are integral with the exterior surface of the center portion and extend radially outwardly therefrom.

8. A hair curler according to claim 6 wherein the protuberances are upstanding rectilinear filaments provided on a flexible tape, the tape being secured to the exterior surface of the center portion.

9. A hair curler according to claim 6 wherein the protuberances are tooth-shaped.
